(57) **CLAIM**

The ornamental design for a cart for a golf bag as shown and described.

DESCRIPTION

FIG. 1 is a top perspective view of a cart for a golf bag.

FIG. 2 is a bottom perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof;

FIG. 8 is a rear elevational view thereof;

FIG. 9 is a front perspective view of a cart for a golf bag showing it in its use state; and,

FIG. 10 is a front perspective view of a cart for a golf bag showing the cart in an alternate position.

The dot-dot-dash broken lines represent boundaries of the claimed design. The dash-dash broken lines show portions of the article and environmental structure that form no part of the claimed design.
